UNITED STATES PATENT OFFICE.

JOHN WALTER PERRY, OF SOUTHPORT, CONNECTICUT.

PROTECTOR FOR CIGARETTES.

Application filed July 29, 1920. Serial No. 399,762.

To all whom it may concern:

Be it known that I, JOHN WALTER PERRY, a citizen of the United States, residing at Southport, county of Fairfield, State of Connecticut, have invented an Improvement in Protectors for Cigarettes, of which the following is a specification.

This invention produces a protector for cigarettes which may be used in connection 10 with the original package in which the cigarettes are put up, an object of the invention being to provide protecting means to make certain that the cigarettes do not become mashed or otherwise materially damaged. Additional objects are to provide a 15 protector equipped with means for properly moistening the cigarettes and for precluding the entrance of moisture from the atmosphere to the original package, and also 20 equipped with means whereby the outside paper container or cover for the original package can be released from the stamp or other means used by manufacturers for closing the exposed portion of the foil wrapping 25 for the cigarettes, in order that the foil wrapping, together with the cigarettes, can be removed from the outside paper container or cover and placed in the protector of the invention, and the protector and its 30 contents can be subsequently placed in said container or cover.

With the above and other objects in view, the invention comprises the construction and arrangement of parts as now to be fully described and hereinafter specifically claimed.

In the accompanying drawing forming a part of this specification,

Fig. 1 is a perspective view of the protector;

Fig. 2 a sectional view thereof;

Fig. 3 a perspective view of the protector and of a package of cigarettes, illustrating the manner in which the stamp or other closing means is disconnected from the container or cover; and

Fig. 4 is a perspective view of the container and of a package of cigarettes, illustrating the manner in which the protector is used.

As is well known certain types of cigarettes now on the market are put up in packages consisting of an outside paper container or cover; A, a foil wrapping; B for the cigarettes, which is inserted in the container or cover, and a stamp C, the opposite ends of which are attached to the out-

side opposite edges of the open end of the container to hold the foil wrapping and cigarettes in place. When the package reaches a consumer, he first tears the stamp 60 and afterwards removes the visible part of the foil wrapping, or a portion thereof, as indicated at D in Fig. 4 so that the cigarettes are readily accessible. Cigarette smokers are aware of the fact that as soon 65 as a few of the cigarettes are removed from the original package, the package is liable to become distorted when being carried on the person so that the remaining unsmoked cigarettes are mashed and otherwise damaged. In fact, it almost always occurs, when 70 a partial package is carried for even a short length of time, that the cigarettes last smoked are badly disfigured. I have found that a number of the paper containers or 75 covers for different makes of cigarettes are of approximately the same size, and to overcome the difficulties encountered by smokers as hereinbefore set forth, the protector of the invention has been designed to be located 80 between the original container or cover and the foil wrapping. That is, the foil wrapping containing the cigarettes is adapted to be located in the protector and the protector is adapted to be then located in the original 85 container or cover. In view of the fact that the foil wrapping as now made by the different manufacturers, loosely fits the paper container or cover, it will be obvious that the protector invented by me can be inserted 90 between said foil wrapping and cover, and will, when inserted, preclude the accidental removal of either the wrapping or cover, while not causing the cigarettes in the foil wrapping to be mashed to the slightest extent.

As will be clear from the drawings, the protector consists of a box having sides 10, ends 11, an open bottom 12 and a top 13. The top is cut away, as indicated at 14 and 100 15 is provided for covering the cut away portion, the slide being equipped with means whereby it may be manipulated adapted to enter a slot 16 in the protector top. The means shown for causing the slide 105 to travel in the slot to cover the cut away portion are tongues 17. Other convenient means may be used.

18 denotes a blotter or other humidor carried by the slide. The bottom edge of either 110 or both sides of the protector is cut away as indicated at 19 to provide a cutter for re-

leasing the stamp from the container or cover as suggested in Fig. 3, the cutter shown constituting convenient means whereby the stamp can be neatly and easily broken. As will be understood, the protector is of proper dimensions to fit between the foil wrapping and container or cover for the original package, and may be constructed of any relatively stiff material suitable for its purposes, 10 such as cardboard, celluloid or metal.

The manner of use will be apparent. When the consumer purchases a package of cigarettes, he first causes the cutter to break the seal. He next lifts the foil wrapping and 15 cigarettes from the paper container or cover. He next removes a portion of the upper end of the foil wrapping to expose a few of the cigarettes, as suggested in Fig. 4. He next inserts the foil wrapping and cigarettes into 20 the open end of the protector so that the exposed ends of the cigarettes lie beneath the cut away portion adapted to receive the slide. The protector is lastly inserted in the paper container or cover open end first. 25 When a cigarette is to be removed from the

protector the slide is moved to open position, toward the left in Fig. 1. The slide normally covers the opening made in the foil wrapping so that the humidor has contact with the cigarettes. As cigarettes are removed, others may be made to come under the opening in the foil wrapping by simply 30 tilting the package in the proper direction, as has heretofore been the practice when cigarette smokers have removed only a portion of the foil wrapping. 35

What I claim is:

As a new article of manufacture, a protector for cigarettes comprising a body shaped to fit a package of cigarettes and 40 having one end open, a cover carried at the other end of said protector body and comprising a rigid section and a slidable section, a side of said body being cut away at its open end to provide a recess, one side of 45 said recess being extended inwardly over the recess at the free edge of the body and sharpened to provide a cutter.

In testimony whereof I affix my signature.

J. WALTER PERRY.
